SEPARATION OF AROMATIC AND SULFUR COMPOUNDS

Arthur P. Lien, Hammond, Ind., and Bernard L. Evering, Chicago, Ill., assignors to Standard Oil Company, Chicago, Ill., a corporation of Indiana

Application July 2, 1946, Serial No. 681,121

12 Claims. (Cl. 196—13)

1

This invention relates to a process for separately recovering aromatic hydrocarbons and sulfur compounds from hydrocarbon oils. More particularly, it relates to a process for treating solutions comprising aromatic hydrocarbon and sulfur compounds with liquid HF-BF₃ mixtures and thereafter recovering separate fractions containing HF-BF₃, aromatic hydrocarbons and sulfur compounds, respectively.

It is known that liquid HF-BF₃ mixtures are solvents for aromatic hydrocarbons and sulfur compounds contained in various hydrocarbon mixtures, for example, in various petroleum fractions wherein they are found in admixture with paraffinic and naphthenic hydrocarbons. The extraction of the aromatic hydrocarbons and sulfur compounds by liquid HF-BF₃ may be accompanied by more or less catalytic cracking, isomerization of paraffin hydrocarbons, alkylation or other reactions, depending on the operating conditions such as temperature, ratio of hydrocarbon charging stock to the HF-BF₃, the concentration of BF₃ in the HF, etc. The primary purpose of the process of treating a hydrocarbon mixture containing aromatic hydrocarbons and sulfur compounds may, in fact, be to effect a chemical conversion of the hydrocarbon charging stock under the catalytic influence of HF-BF₃ mixtures, and the extraction of aromatic hydrocarbons and sulfur compounds by liquid HF-BF₃ mixtures may be incidental to said conversion.

One object of our invention is to provide a process for the separate recovery of aromatic hydrocarbons and sulfur compounds from materials containing the same, for example, petroleum hydrocarbon mixtures such as crude oil, lubricating oil fractions, gas oil, gasoline, naphthas and the like, or from coal tar fractions. Another object of our invention is to provide a process for the preferential dissociation of co-ordination compounds of aromatic hydrocarbons-BF₃-HF in the presence of co-ordination compounds of sulfur compounds-HF-BF₃. An additional object of our invention is to provide a process for the separation of boron fluoride from co-ordination compounds thereof with aromatic hydrocarbons and sulfur compounds. Further objects of our invention will become apparent from the ensuing description thereof, read in conjunction with the accompanying schematic flow diagram.

We have discovered a novel process for the liberation of aromatic hydrocarbons from solutions thereof in liquid hydrogen fluoride-boron fluoride mixtures which also contain sulfur compounds. We have also discovered a process for the

2

separate recovery of aromatic hydrocarbons and organic sulfur compounds from solutions thereof in liquid hydrogen fluoride-boron fluoride mixtures, preferably mixtures containing a minor proportion of boron fluoride between about 1 and about 40 weight per cent, based on the weight of hydrogen fluoride.

Solutions of aromatic hydrocarbons in liquid HF-BF₃ have heretofore been prepared and it has been proposed to liberate aromatic hydrocarbons therefrom by distilling HF and BF₃ from said solutions at a low temperature, for example, about 19° C., as set forth in U. S. Patent 2,343,841 of R. E. Burk. However, it has not heretofore been appreciated that aromatic hydrocarbons and organic sulfur compounds could be separately regenerated from their joint solution in liquid HF-BF₃.

In the interests of simplifying the nomenclature used herein, we refer to "solutions" of aromatic hydrocarbons and organic sulfur compounds in liquid HF-BF₃, although we appreciate the fact that these are not simple solutions in the ordinary sense of the term. Rather, it appears that BF₃ or BF₃ and HF unite chemically in the so-called "solutions" with aromatic hydrocarbons and organic sulfur compounds to produce co-ordination compounds i. e., more or less stable chemical compounds sometimes known as "complexes," and these co-ordination compounds are soluble in the HF component of the solution, which is present in excess. Free HF is present in the solutions and preferably also some free BF₃.

We have discovered that co-ordination compounds of aromatic hydrocarbons with BF₃ and HF can generally be more readily dissociated than co-ordination compounds of organic sulfur compounds with BF₃ and HF. When the aromatic hydrocarbon co-ordination compounds are heated to temperatures between about 100° F. and about 200° F., preferably between about 120° F. and about 160° F., appreciable dissociation occurs, resulting in the liberation of free HF and BF₃ on the one hand, and aromatic hydrocarbons on the other. In a preferred form of our invention, dissociation of the aromatic hydrocarbon co-ordination compounds is effected with simultaneous vaporization of HF and BF₃ and their removal from the dissociation zone at about the rate at which they are formed, tending thus to increase the degree of completion of the dissociation reaction. The dissociation of the aromatic hydrocarbon co-ordination compounds can be effected at super-atmospheric pressures, e. g., between about 5 and about 100 p. s. i., but it is preferable to con-

duct the dissociation and distillation of HF and BF₃ at atmospheric pressure or even at subatmospheric pressures between about 0.2 and about 10 p. s. i. absolute.

The removal of HF and BF₃ accompanying dissociation of the aromatic hydrocarbon co-ordination compounds is also very important for the reason that, as these fluorides are removed, free aromatic hydrocarbons separate from the solution and can be recovered, preferably in a zone 10 separate from the dissociation zone by gravity separation methods, e. g., settling, decantation, or centrifuging. Simultaneously, a stratum of higher specific gravity than the aromatic hydrocarbons separates from the solution which has been substantially denuded of HF and BF₃. The relatively higher specific gravity stratum consists of co-ordination compounds of organic sulfur compounds with BF₃ and HF and may contain a small proportion of free HF and BF₃.

We have found that the co-ordination compounds of sulfur compounds referred to above are more resistant to dissociation than the co-ordination compounds of aromatic hydrocarbons and that a higher temperature is therefore necessary to liberate BF₃ and HF from said co-ordination compounds of organic sulfur compounds. Specifically we have found that temperatures in the general range of about 160° F. to about 500° F. are necessary to dissociate said co-ordination compounds of the organic sulfur compounds, and preferred temperatures are between about 200° F. and about 400° F. The dissociation of the co-ordination compounds of organic sulfur compounds can be effected under a super-atmospheric pressure, for example, between about 5 and about 100 p. s. i., but is preferably conducted at substantially atmospheric pressure or even at subatmospheric pressures, with removal of free HF and BF₃ from the dissociation zone at substantially the rate at which they are evolved. Inert gases may be passed through the zones wherein co-ordination compounds of aromatic hydrocarbons or sulfur compounds are being dissociated in order to facilitate stripping of HF and BF₃ from said zones. Suitable inert gases include carbon dioxide, nitrogen, methane, ethane, propane and the like.

Our process finds its preferred application to light gas oil and lower boiling hydrocarbon oils. In general, we have found that the lighter the feed stock, the greater the degree of selectivity of separation of sulfur compounds and aromatic hydrocarbons.

In order to illustrate, but not to limit, our invention reference is made to the accompanying schematic flow diagram which depicts one embodiment of our process. The charging stock can be any liquid hydrocarbon mixture containing aromatic hydrocarbons and organic sulfur compounds. The charging stock may be, for example, a petroleum gas oil containing aromatic hydrocarbons and organic sulfur compounds, or a distillate or residual lubricating oil fraction. It should preferably be in a substantially anhydrous condition. Predrying of the charging stock can be effected by conventional processes for drying hydrocarbon oils, as by percolation through a bed of adsorptive alumina or silica gel, or may be effected by contacting the charging stock with an aqueous HF-BF₃ mixture, e. g., aqueous HF-BF₃ produced in the process because of the gradual accumulation of water in the reaction system even when a pre-dried charging stock is employed.

It is desirable to reduce the viscosity of viscous

charging stocks by dilution thereof with a suitable amount of a light paraffinic hydrocarbon, e. g., pentane, hexane or a paraffinic gasoline or naphtha fraction. The low boiling paraffinic diluents serve not only to reduce the viscosity of the charging stock, thereby facilitating contacting operations, but also aid in the recovery of HF from the treated charging stock, as will be explained hereinafter.

The charging stock is introduced from source 10 by pump 11 through line 12, heater 13 and line 14 to a low point in contacting vessel 15. Make-up HF and BF₃ are introduced into line 14 through line 17 although a portion may be introduced through line 18. Generally speaking we prefer to employ liquid HF-BF₃ mixtures which are substantially anhydrous or which contain only a trace of water, i. e., an amount of the order of 0.01 to 1 weight per cent and in any case not more than about 3 weight per cent. We prefer to employ mixtures containing between about 1 and about 40 weight per cent of boron fluoride based on the weight of hydrogen fluoride, although we may employ solutions wherein the weight of boron fluoride is in excess of the weight of hydrogen fluoride. In contactor 15, which is preferably provided with suitable means of agitation (not shown) the hydrocarbon charging stock is treated under controlled conditions of time, pressure, temperature and ratio of charging stock to HF-BF₃. The contacting operation may involve simply the extraction of aromatic hydrocarbons and sulfur compounds from the charging stock or it may involve chemical conversion of the charging stock as a principal or incidental process, the operating conditions being suitably adjusted to effect the desired purpose.

For example, extraction of aromatic hydrocarbons and organic sulfur compounds from hydrocarbon fractions containing the same, for example, petroleum or coal tar fractions may be effected at temperatures between about -30° F. and about 200° F., preferably at temperatures between about 65° F. and about 85° F. The pressure in contactor 15 is ordinarily adjusted to maintain the charging stock and a substantial proportion of the HF-BF₃ in the liquid phase. We prefer to employ BF₃ in an amount sufficient to exert a positive partial pressure, e. g., 5 to 200 p. s. i. g. The existence of a positive partial pressure of BF₃ in the contacting zone indicates that BF₃ is present in an amount in excess of that which is necessary to combine with aromatic and sulfur compounds in the charging stock. Between about 5 and about 300 volume per cent of the liquid HF-BF₃ mixture or even more may be used, based on the volume of hydrocarbon charging stock although, generally, amounts between about 10 and about 100 volume per cent are employed.

A portion of the sulfur compounds in the charging stock can be converted to H₂S by charging hydrogen, also, to contactor 15. A hydrogen partial pressure between about 50 and 3,000 p. s. i. g., preferably about 200 to about 2,000 p. s. i. may be employed. Increased hydrogenation may be effected by employing a nickel liner in contactor 15. When hydrogen is employed, we prefer to use temperatures between about 150° F. and about 500° F., preferably about 250° F. to about 400° F.

If a hydrocarbon charging stock such as gas oil containing both aromatic hydrocarbons and organic sulfur compounds is to be cracked in contactor 15, temperatures between about 100° F.

and about 400° F. may be employed. Usually a temperature of the order of about 212° F. is suitable, preferred temperatures ranging between about 180° F. and about 300° F. The pressure in the contacting zone will be adjusted to maintain substantially liquid phase conversion conditions. At a temperature of about 212° F. the pressure may be of the order of 400 p. s. i. g. The charging stock is caused to pass upwardly through a liquid column of catalyst in the contacting zone at a space velocity which may be about 1 volume of charging stock per hour per volume of catalyst in the reactor, although space velocities between about 0.2 and about 4 may be used. The cracking catalyst comprises liquid HF-BF₃ mixtures which may contain between about 1 and about 40 per cent by weight of BF₃ based on the HF.

It should be understood that the ratio of catalyst to charging stock in the cracking process may vary depending upon the type of charging stock and the operating conditions which it is desired to employ in contacting zone 15. Generally speaking larger amounts of catalyst are required with charging stocks of more refractory character, i. e., stocks more deficient in hydrogen and richer in aromatic hydrocarbons, and lesser amounts of catalyst are required with relatively clean or more highly paraffinic charging stocks. The weight ratio of hydrocarbon to catalyst introduced into the reactor may thus vary from about 10:1 to 1:2.

Contacting may be effected in any suitable type of contactor on a batchwise, multiple batch, semi-continuous or continuous basis but we prefer to employ a continuous process with a tower type contactor and to pass the charging stock upwardly through a column of the liquid HF-BF₃ mixture with or without mechanical agitation. We may use concurrent or countercurrent contacting. The contactor may be of the type described in U. S. Letters Patent No. 2,238,802 and No. 2,349,821. It may be about 5 to 50 feet high and should be designed to withstand a maximum operating pressure which, with high temperatures, may be as much as 1000 p. s. i. g. or more. Before contacting is initiated the contactor may be filled about 1/2 to 3/4 full of the liquid HF-BF₃ and its temperature may be adjusted as desired by conventional means. The bulk of the fluoride solution separates from the effluent product stream in the upper part of the contactor although some of the fluoride solution is carried with the effluent product stream through line 19 and cooler 20 to separator 21. Fluoride material which settles out in this settler or separator can be returned by lines 23 and 24 to contactor 15, a pump 22 being employed when separator 21 is operated at a pressure below the reactor pressure or if the settler is not elevated sufficiently to insure gravity return.

Boron fluoride together with a small amount of fixed gases which may be produced can be vented from the top of separator 21 through line 25 and passed through line 26 which leads to the base of absorber 27. The remaining liquid product stream flows over weir 28 and passes by line 29 to BF₃ stripper 30 which is provided with a suitable reheating means or reboiler 31 at its base. Line 29 may be provided with a suitable pressure reducing valve or pump depending upon the relative pressures in separator 21 and stripper 30 respectively. The stripper may operate at a pressure of about 200 or 300 p. s. i., for example about 250 p. s. i., and sufficient heat is supplied to

insure the removal of substantially all of the BF₃ which passes by line 32, compressor 33 (if necessary), and line 26 to the base of absorber 27. Make-up BF₃ can be supplied from source 34 and introduced into the contacting system by compressor 35 to line 26.

After removal of BF₃, the product stream passes by line 36 to azeotropic distillation still 37 which is provided with a suitable reheating means or reboiler 37' at its base and which may be provided with reflux means at its top. In the azeotropic still the HF is distilled with a light paraffin hydrocarbon such as propane, butane, pentane, etc. which may have been introduced with the charging stock to serve also as a viscosity-reducing diluent, or may be introduced into the still from source 41 and valved line 42 through settler 43, line 46 and reflux pump 47. In the operation of the azeotropic still, a butane-HF azeotrope, for example, passes overhead through line 38, condenser 39 and lines 40 and 42 to settler 43, which is operated at as low a temperature as can be obtained with available cooling water, preferably well below 100° F. The condensed azeotrope separates into a heavier HF stratum which is withdrawn by line 44 to HF storage tank 45. The upper butane stratum is returned by line 46 and pump 47 to still 37 and may eventually leave the still with the product stream through line 49. Light gases may be vented from settler 43 through valved line 48; such gases should contain no BF₃, but if they do, they can be introduced through line 26 to absorber 27.

The product stream is withdrawn from the base of the azeotropic still 37 through line 49. The product stream is usually substantially free from organic fluorides and hence may require no special treatment for their removal. Conventional bauxite or equivalent treating system 50 is preferably employed at this point, however, to remove any traces of fluorides which may be present. The product stream leaves the fluoride removal zone by line 51 and may, if desired, be subjected to further finishing treatments as may, in the specific case, be required or desirable, such as fractional distillation, washing, contacting with active absorbent clay or the like.

It should be understood that we are not restricted to azeotropic distillation for the purpose of removing HF from the products. Ordinary or flash distillation may be used for this purpose.

A solution of BF₃, aromatic hydrocarbons and sulfur compounds in liquid HF is withdrawn from contactor 15 through line 52 or from settler 21 through lines 23 and 53 and passed through pressure reducing valve 54 to a recovery drum 55 which is preferably operated near atmospheric pressure, for example, at about 5 to about 50 lbs. gauge pressure and at a temperature between about 100 and about 200° F., preferably between about 120 and about 160° F. Under these conditions co-ordination compounds of aromatic hydrocarbons and BF₃ are dissociated and free HF and BF₃ are vaporized and passed overhead through line 56. This mixed effluent may pass directly through condenser 57 to receiver 58, where HF is collected as a liquid and from which BF₃ may be flashed overhead through line 59 to line 18. Liquid HF may be pumped from receiver 58 through line 60 and pump 61 to HF storage tank 45, provided with a valved vent line 45'. There is a tendency for moisture to accumulate in the system even when substantially dry charging stocks are employed because of the

extremely hygroscopic nature of HF and BF_3 ; to remove moisture from these fluorides it is desirable, from time to time, to introduce the effluent from line 56 through valved line 62 into distillation column 63 provided with heating means 64. In distillation column 63, substantially anhydrous HF and BF_3 are vaporized and pass overhead through line 65 and condenser 57 to receiver 58. A portion of the condensate in receiver 58 is returned through line 66 to serve as reflux in distillation column 63. Aqueous HF- BF_3 may be withdrawn from the base of column 63 through line 67 and treated by known methods for the recovery of the fluoride components. A portion of the aqueous HF- BF_3 may be used to pre-dry the charging stock to the process.

Heating of the materials in drum 55 results in dissociation of the BF_3 -HF aromatic hydrocarbon co-ordination compounds or complexes and distillation of HF and BF_3 , whereby the aromatic hydrocarbons are thrown out of solution. The residue in drum 55, comprising aromatic hydrocarbons and sulfur compound co-ordination compounds, is withdrawn through line 68 to settler 69 wherein an upper stratum of aromatic hydrocarbons is formed and can be recovered from the lower stratum of sulfur-containing co-ordination compounds and is removed by line 18 for such further treatment as may be required or desirable, e. g., washing with water or alkaline solutions such as ammonia, contacting with adsorbent clays or bauxite and fractional distillation into fractions of desired boiling range. The aromatic hydrocarbons recovered by the process of our invention may be used in the preparation of high solvency naphthas or valuable materials for organic synthesis.

The complex material which settles out in settler 69 is withdrawn through valved line 71 to recovery drum 72 which is provided with heating means 73. This drum is operated, preferably at about atmospheric pressure, although higher pressures of the order of about 5 to about 50 lbs. per square inch may be used, and at temperatures between about 160° F. and 500° F., preferably between about 250° F. and about 350° F. Under these conditions co-ordination compounds of BF_3 -HF-sulfur compounds are dissociated and free HF and BF_3 are vaporized and passed overhead through line 18, compressor 74 and line 18' into absorber 27 or through line 14 into contactor 15. It is preferably to pass the effluents of line 18 to absorber 27, this arrangement offering the advantages of providing better control of the amount and composition of the HF- BF_3 mixture entering contactor 15 and the possible elimination of compressor 74.

A concentrate of organic sulfur compounds is withdrawn from drum 72 through line 75 and may be subjected to such finishing treatments as are required or desirable, e. g., washing with ammonia or aqueous alkalies, fractional distillation and the like. The organic sulfur compounds can be adapted to various uses such as manufacture of extreme pressure agents for lubricating oils and greases, oxidation to sulfonic acids or other organic syntheses.

Further purification and concentration of the aromatic hydrocarbons and sulfur compounds withdrawn respectively through lines 70 and 75 can be effected by subjecting them, separately, to repeated extraction with liquid HF- BF_3 mixtures containing, preferably, between about 1 and about 40 weight per cent of BF_3 based on the HF.

These treating operations may be effected in contractors of the type of contactor 15; the apparatus used for re-treating may, in fact, essentially duplicate the contacting, settling and fractionation equipment described for use in the main treating operation. The re-treating operations may be carried to a sufficient length to obtain essentially pure aromatic hydrocarbons free from organic sulfur compounds and organic sulfur compounds substantially free of aromatic hydrocarbons.

In our studies of the desulfurization of hydrocarbon oils containing aromatic hydrocarbons and organic sulfur compounds, we have observed that BF_3 or liquid HF- BF_3 mixtures extract appreciable quantities of sulfur compounds before the extraction of aromatic hydrocarbons is initiated. The extraction of aromatic hydrocarbons from the feed stock begins only after variable proportions of the organic sulfur compounds have been extracted, depending on the boiling range of the charging stock. For example, in the extraction of 750 cc. of furnace oil from Slaughter crude oil, containing 1.46 weight per cent of sulfur in the form of organic sulfur compounds in sequence with a solvent consisting of 10 grams of liquid HF and with 34 grams of BF_3 -10 grams of HF for $\frac{1}{2}$ hour at 70-74° F. under a pressure of 25 p. s. i. g., we have observed that 72 weight per cent of the sulfur was removed but that this degree of sulfur removal was accompanied by only a slight change in refractive index (from n_{D}^{20} of 1.4771 to 1.4680) and specific dispersion (from 129 to 124), indicating that substantially no aromatic hydrocarbons had been extracted from the feed stock. However, above this level of sulfur compound extraction, aromatic hydrocarbons were being extracted in rapidly increasing quantity as evidenced by a rapid drop in the specific dispersion of the refined oil.

We have also extracted a heavy naphtha containing 0.39 weight per cent of sulfur in the form of organic sulfur compounds with 50 cc. of HF and 10 grams of BF_3 per liter of naphtha for one hour at about 80° F., followed by a gravity separation of a hydrogen fluoride solution (extract phase) and a lower specific gravity stratum (refined naphtha or raffinate phase). It was observed in this experiment that although 94 weight per cent of the sulfur was extracted from the naphtha, the specific dispersion of the naphtha remained unchanged at a value of 116, indicating that no aromatic hydrocarbons were extracted from the naphtha. However, under conditions leading to more thoroughgoing extraction of the organic sulfur compounds from the naphtha we have found that aromatic hydrocarbons are simultaneously extracted with the organic sulfur compounds.

It is thus possible, by careful control of the quantity of HF- BF_3 to extract substantially all the organic sulfur compounds from solutions with aromatic hydrocarbons, preferably by multiple batch extractions.

We have also observed that liquid, substantially anhydrous HF exhibits different solvent properties from BF_3 solutions in liquid HF. Whereas liquid HF- BF_3 mixtures exhibit a pronounced capacity to dissolve and extract aromatic hydrocarbons of the most diverse types, e. g., mono- or polynuclear aromatics and benzoid- (e. g., phenanthrene) or quinonoid type (e. g., anthracene) aromatic hydrocarbons, liquid HF alone is much more selective in its action

and extracts little or no mononuclear aromatic hydrocarbons or benzenoid type polynuclear aromatic hydrocarbons while exhibiting a marked solvent power towards quinonoid-type polynuclear aromatic hydrocarbons such as anthracene. However, liquid HF, like BF_3 solutions in liquid HF, is a good solvent for organic sulfur compounds.

We have noted that hydrocarbon charging stocks containing organic sulfur compounds can be practically desulfurized by treating with HF vapor. The sulfur compounds and some polynuclear aromatic hydrocarbons in the charging stock react with some of the HF forming a complex which is insoluble in the oil and the complex can be gravity separated as a liquid along with dissolved HF.

Thus, it is possible to treat mixtures of organic sulfur compounds and aromatic hydrocarbons of the type which are not markedly soluble in liquid HF with liquid HF in an amount sufficient to extract a substantial proportion of the sulfur compounds, preferably by multiple batch extraction, in order to obtain sulfur-free aromatic hydrocarbons on the one hand and organic sulfur compounds substantially free of aromatic hydrocarbons on the other.

Make-up HF can be added to the system from source 76 to storage tank 45. Hydrogen fluoride is pumped from this storage tank by pump 77 and passed by line 78 to the upper part of absorber 27 which may be operated at a pressure between about 50 and about 400 p. s. i. or higher, e. g., about 250 p. s. i. At such pressures and at a relatively low temperature of the order of about 100° F. the BF_3 is absorbed in the HF but hydrocarbon gases are not absorbed therein and may be vented from the top of the absorber through valved line 79. By this means losses of BF_3 are substantially prevented while the system is being purged of methane or other light gases which may tend to accumulate in the system as the result of cracking or other reactions. It should be understood that make-up HF can be introduced directly into the top of the absorber and that line 44 and/or 60 may likewise lead to the absorber rather than to an HF storage tank.

Our invention is not limited to the use of HF as an absorbent for BF_3 since any other selective absorbent liquid may be employed. An intimate liquid mixture or solution of HF and an aromatic hydrocarbon (particularly an alkyl aromatic hydrocarbon containing 7 to 11 carbon atoms per molecule) is particularly advantageous because BF_3 reacts with such mixture to form a complex which is soluble in liquid HF. Thus, we may introduce such alkyl aromatics (for example a portion of the aromatic hydrocarbons from line 70) into the upper part of the absorber through line 80 and we may obtain an intimate mixture of such aromatics and HF either by the manner in which these liquids are introduced into the absorber tower or by the use of mechanical means.

Any BF_3 which is not absorbed in the HF in the lower part of the absorber will thus be chemically combined with the HF-aromatic mixture at the top of the absorber so that practically no BF_3 will leave the top of the tower with extraneous gases even when the absorber is operated at pressures as low as atmospheric pressures. By this method of operation we may avoid the necessity of employing compressors 33 and 74 and likewise avoid the necessity of operating drum 72 at the higher temperatures and pressures which

would be required for the introduction of liberated HF and BF_3 into a high pressure absorber.

When liquid HF alone is used to absorb the BF_3 , the resulting solution is passed into contactor 15 through valved line 17 and line 14. When appreciable quantities of aromatic hydrocarbons are employed in absorber 27 to aid in the absorption of BF_3 , it is preferable to pass all or a substantial proportion of the resulting solution through line 17 and valved line 81, thence through pressure reducing valve 54 into recovery drum 55 in order to separate aromatic hydrocarbons from the fluoride components prior to the introduction of the latter into contactor 15.

Although in referring to the accompanying schematic flow diagram we have described a process wherein HF and BF_3 are used together, it should be understood that our invention is not thus limited. Although aromatics whose normal boiling points are below 600° F. are not appreciably soluble at ambient temperatures in liquid hydrogen fluoride, some of the aromatics having boiling points above 600° F. are appreciably soluble at ambient temperatures in liquid hydrogen fluoride. Thus in the case of a charging stock that contains HF-soluble high boiling aromatics, it is possible, if desired, to take advantage of the peculiar solvent powers of liquid, substantially anhydrous HF. Using HF alone as the solvent it is not possible, however, to separately recover aromatic hydrocarbons and sulfur compounds from their solution in the hydrogen fluoride. However, HF alone could be used in the operation of contactor 15 following which a hydrogen fluoride extract phase withdrawn through line 52 could be contacted in a separate zone (not shown) with BF_3 and the BF_3 -enriched extract phase could thereafter be passed into recovery drum 55. However, treatment of the hydrogen fluoride extract phase with BF_3 results in a production of co-ordination compounds with aromatic hydrocarbons and organic sulfur compounds respectively, which co-ordination compounds can be differentiated and separated on the basis of their different thermal stabilities, as pointed out above. Conversely the charging stock can first be contacted with BF_3 alone in contactor 15, following which a BF_3 -containing phase is withdrawn through line 52 and can be treated in a separate zone (not shown) with liquid HF to produce a solution which is passed into recovery drum 55 in order to institute operations for the recovery of the components of the solution.

The following examples are adduced in order to illustrate, but not unduly to limit, the results obtainable by the process of our invention.

EXAMPLE I

In order to demonstrate the effect of BF_3 -HF mixture as a desulfurizing agent, a sample of Mid-Continent virgin gas oil containing 0.12 per cent sulfur was treated in two steps (A and B) as shown in the following table:

	A	B
HF, g.	384	
BF_3 , g.	70	47
Feed, g.	580	414
Temp., ° F.	45	120
Time, min.	15	60

Upon completion of step A, a 445 g. sample of raffinate was withdrawn for analysis, following which 414 additional grams of charging stock were added to the remaining reactor contents to

11

gether with 47 grams of BF_3 . Contacting in both steps was effected in a 1570 cc. carbon steel bomb fitted with a 1725 R. P. M. stirrer and a bleed-off tube terminating at a point well above the liquid level of the liquid HF solution, allowing ready removal of supernatant raffinate. Upon completion of the second step, the raffinate and HF phases were separated by settling and were treated as pointed out below.

It was noted that the amount of BF_3 required to give a positive pressure on the reactor in these runs was several times that required for ordinary paraffinic charging stocks. This observation, coupled with the fact that in the two runs a total of 85 grams of BF_3 remained bound in the catalyst phase, indicates the formation of BF_3 complexes. The fact that only 2.5 grams of BF_3 would be consumed by reacting mol for mol with the sulfur present indicates the formation of a BF_3 -aromatic hydrocarbon complex; this is further borne out by the analysis shown below, as well as discussed more fully hereinafter.

The catalyst layer (HF phase) (611 g.) from the above runs was subjected to dissociative distillation at 190° F. to remove HF- BF_3 . At this comparatively low temperature, 68 g. of BF_3 distilled and were collected, indicating that the BF_3 -aromatic complex, is a rather loosely-held addition compound. Most of the HF originally added to the reactor also distilled over at temperatures below 190° F., along with some organic material. Upon removal of a substantial proportion of the free HF and BF_3 by distillation, the catalyst layer separated upon standing into a supernatant aromatic hydrocarbon stratum and a lower stratum comprising principally co-ordination compounds of BF_3 -HF-organic sulfur compounds.

The following tabulation presents a comparison of the charging stock and the products produced in each step.

	Feed	Raffinate (A)	Raffinate (B)	Aromatic Layer
Boiling Range, ° F.	442-648	-----	112-624	400-800
Avg. Volumetric B. P., ° F.	510	-----	467	-----
Specific Gravity	0.835	0.814	0.795	0.94
n_{D}^{20}	1.4630	1.4487	1.4480	1.5515
Specific Dispersion	115	99.5	-----	187
Sulfur Content, Wt. Per cent	0.12	0.0	0.0	0.16

The hydrocarbon product (raffinate) from the above runs was water-white as compared to the straw-colored feed. As shown in the above table the sulfur content was reduced to zero indicating that the HF- BF_3 medium is a very efficient agent for extraction of sulfur from hydrocarbons, either at 45° or 120° F. The process appears to take place through the formation of an addition complex between sulfur compounds and BF_3 , followed by solution of this complex in the liquid HF phase.

Of considerable interest is the fact that substantial quantities of aromatics have been removed from the original gas oil and that the resultant product is highly paraffinic as shown by specific dispersions, refractive indices and specific gravities. Corresponding to disappearance of aromatics from the upper hydrocarbon phase is the fact that the catalyst phase increased substantially in volume and that the hydrocarbon obtained from the catalyst layer in the manner described below is very highly, if not completely, aromatic as shown by the physical properties listed in the above table.

The residue remaining after dissociation of

12

aromatic-co-ordination compounds and distillation of excess HF and BF_3 consisted of two distinct layers. The upper layer, light in color, proved to be highly aromatic as previously mentioned. The bottom layer was quite dark and viscous, apparently consisting of an organically bound BF_3 -sulfur compound complex. Heating this complex to 358° F. resulted in the liberation of 10 g. BF_3 , which, together with the 68 g. recovered on the original heating at 190° F., gives a total recovery of 78 g. as compared to the 85 g. which disappeared into the catalyst during the two runs (the remainder of BF_3 was bled out with the gases leaving the reactor).

15

A transformer distillate from Winkler crude oil, which distillate contained 1.54 per cent sulfur, was treated in sequence at 50° F. with varying amounts of BF_3 as shown in the following table. The same reactor was used as in Example I.

Treatment of Winkler transformer distillate with HF- BF_3

	Conditions	C	D
25	HF, g.-----	400	-----
	BF_3 , g.-----	21	91
	Feed, g.-----	640	448
	Temp., ° F.-----	50	50
30	Time, min.-----	15	15

In run C just enough BF_3 was added to provide one mol of BF_3 per mol of sulfur in the feed. The 21 g. of BF_3 thus added was completely absorbed, leaving no pressure on the reactor and liberating no BF_3 on bleeding out the product. As shown in the following table the raffinate (product) retained a substantial amount of sulfur as well as aromatics, the content of the latter being indicated by specific dispersion, refractive index and specific gravity. Upon completion of run C, a 426 g. sample of raffinate was withdrawn for analysis and an additional 448 g. of distillate and 91 g. of BF_3 were added to the reactor to carry out run D.

45 In run D, an excess of BF_3 was used, i. e., sufficient to give a positive pressure of 65 p. s. i. on the reactor contents when stirred at 50° F. Of the 91 g. of BF_3 added, only 25 g. were recovered on bleeding out the product. As shown in the 50 table, the sulfur compound removal was good and most of the aromatics were extracted to give a substantially paraffinic-naphthenic raffinate.

55 Approximately 300 g. of the 1088 g. of hydrocarbon treated in the two runs went into solution in the liquid HF layer. The sulfur content of this layer was 5.6 weight per cent. On heating this layer to 190° F. HF distilled off. After distillation of the material boiling up to 190° F., the residue separated by gravity into two layers. The upper 60 layer was transparent and, as shown by the data in the table, consisted substantially of aromatic hydrocarbons. The bottom layer was a black complex which was hydrolyzed with aqueous ammonia (on heating) to give a product with the properties listed in the last column of the following 65 table:

	Feed ¹	Raffinate (C)	Raffinate (D)	Aromatic Layer	Sulfur-Complex
70	Sulfur, Wt. Per Cent-----	1.54	0.33	0.04	2.0
	n_{D}^{20} -----	1.4998	1.4864	1.4659	1.5392
	Specific Gravity-----	0.85	0.880	0.85	0.95
	Sp. Dispersion-----	141	125	102	181

¹ Boiling Range, 537-708° F.

It will be noted that, in both examples, the aromatic layer obtained contains about the same amount of sulfur as the charging stock but markedly less sulfur than that of the total extract or of the separated sulfur layer.

Having thus described our invention what we claim is:

1. The process of regenerating aromatic hydrocarbons from a solution of aromatic hydrocarbons and sulfur compounds in liquid HF-BF₃, said solution comprising co-ordination compounds of BF₃ and HF with aromatic hydrocarbons and organic sulfur compounds, which process comprises subjecting said solution to a dissociative distillation operation at a temperature between about 100° F. and about 200° F., separating a distillate comprising HF and BF₃ from said distillation operation, separating a distillation residue comprising free aromatic hydrocarbons and HF-BF₃ co-ordination compounds of organic sulfur compounds, subjecting said residue to gravity separation, and separately recovering an aromatic hydrocarbon fraction and a fraction comprising co-ordination compounds of organic sulfur compounds.

2. A process of treating a solution of aromatic hydrocarbons and sulfur compounds in liquid HF-BF₃, which process comprises subjecting said solution to dissociative distillation at a temperature between about 100° F. and about 200° F., recovering a distillate comprising HF and BF₃, separating a distillation residue comprising aromatic hydrocarbons and co-ordination compounds of BF₃-HF-organic sulfur compounds, subjecting said residue to gravity separation and separately recovering an aromatic hydrocarbon fraction and a fraction comprising co-ordination compounds of organic sulfur compounds, and subjecting the last named fraction to dissociative distillation at a temperature between about 160° F. and about 500° F.

3. A hydrocarbon treating process which comprises contacting a hydrocarbon charging stock containing aromatic hydrocarbons and organic sulfur compounds with liquid HF containing BF₃ under conditions adapted to form a solution of aromatic hydrocarbons and sulfur compounds in said liquid HF, subjecting said solution to dissociative distillation at a temperature between about 100° F. and about 200° F. and recovering as a distillate fraction a substantial proportion of HF and BF₃ therein contained, recovering a residue from said distillation and subjecting the same to gravity separation, separately recovering an aromatic hydrocarbon fraction and a fraction of higher specific gravity comprising co-ordination compounds of BF₃-HF-organic sulfur compounds from said gravity separation, and recycling at least a portion of said distillate fraction to said hydrocarbon treating process.

4. A hydrocarbon treating process which comprises contacting a hydrocarbon charging stock containing aromatic hydrocarbons and organic sulfur compounds with liquid HF containing BF₃ under conditions adapted to form a solution of aromatic hydrocarbons and sulfur compounds in said liquid HF, subjecting said solution to dissociative distillation at a temperature between about 100° F. and about 200° F. and recovering as a distillate fraction a substantial proportion of HF and BF₃ therein contained, recovering a residue from said distillation and subjecting the same to gravity separation, separately recovering an aromatic hydrocarbon fraction and a fraction of higher specific gravity comprising co-ordination

compounds of BF₃-HF-organic sulfur compounds from said gravity separation, subjecting said fraction of higher specific gravity to dissociative distillation at a temperature between about 160° F. and about 500° F. and separately recovering HF-BF₃ and organic sulfur compounds, and recycling at least a portion of the HF and BF₃ derived from said dissociative distillation operations to said hydrocarbon treating process.

5. A hydrocarbon treating process which comprises contacting a hydrocarbon charging stock containing components boiling above about 600° F. and containing organic sulfur compounds and aromatic hydrocarbons with liquid HF under conditions adapted to form a solution of aromatic hydrocarbons and organic sulfur compounds in said liquid HF, contacting said solution with BF₃ to produce a second solution, subjecting said second solution to a dissociative distillation operation at a temperature between about 100° F. and about 200° F., separating a distillate comprising HF and BF₃ from said distillation operation, separating a distillation residue comprising free aromatic hydrocarbons and co-ordination compounds of organic sulfur compounds, subjecting said residue to gravity separation, and separately recovering an aromatic hydrocarbon fraction and a fraction comprising co-ordination compounds of organic sulfur compounds, subjecting the last named fraction to thermal dissociation at a temperature between about 160° F. and about 500° F. and separating a fraction comprising HF-BF₃ and a fraction comprising organic sulfur compounds.

6. The process of claim 5 wherein the charging stock is a gas oil containing organic sulfur compounds and aromatic hydrocarbons.

7. The process of claim 5 wherein the charging stock is a lubricating oil containing organic sulfur compounds and aromatic hydrocarbons.

8. The process of claim 4 wherein hydrocarbon treating is effected under substantially non-cracking conditions.

9. The process of claim 5 wherein the hydrocarbon treating is effected under substantially non-cracking conditions.

10. The process of claim 2 wherein the first named dissociative distillation is effected at a temperature between about 120° F. and about 160° F. and wherein the last named dissociative distillation step is carried out at a temperature between about 200° F. and about 400° F.

11. The process of claim 4 wherein the first named dissociative distillation step is carried out at a temperature between about 120° F. and about 160° F. and wherein the last named dissociative distillation step is carried out at a temperature between about 200° F. and about 400° F.

12. A hydrocarbon treating process which comprises contacting a hydrocarbon charging stock containing components boiling above about 600° F. and containing organic sulfur compounds and aromatic hydrocarbons with liquid HF under conditions adapted to form a solution of aromatic hydrocarbons and organic sulfur compounds in said liquid HF, contacting said solution with BF₃ to produce a second solution, subjecting said second solution to a dissociative distillation operation at a temperature between about 100° F. and about 200° F., separating a distillate comprising HF and BF₃ from said distillation operation, separating a distillation residue comprising free aromatic hydrocarbons and co-ordination compounds of organic sulfur compounds, subjecting said residue to gravity separation, and separately

15

recovering an aromatic hydrocarbon fraction and
a fraction comprising co-ordination compounds
of organic sulfur compounds.
